UNITED STATES PATENT OFFICE.

GEORG OSCAR WIHS, OF KLEINSCHMALKALDEN, AND OTTO PETRI, OF STUTTGART, GERMANY, ASSIGNORS TO THE FIRM OF DAIMLER-MOTOREN-GESELLSCHAFT, OF UNTERTÜRKHEIM, NEAR STUTTGART, GERMANY.

MOTOR-PLOW.

1,148,420.

Specification of Letters Patent. Patented July 27, 1915.

Application filed February 26, 1915. Serial No. 10,809.

To all whom it may concern:

Be it known that we, GEORG OSCAR WIHS, a subject of the German Emperor, residing at Kleinschmalkalden, in the Duchy of Gotha, Germany, manufacturer, and OTTO PETRI, a subject of the King of Wurttemberg, residing at Stuttgart, in the Kingdom of Wurttemberg, Germany, engineer, have invented certain new and useful Improvements in Motor-Plows, of which the following is a specification.

This invention relates to motor plows and more especially to a motor plow connected with a frame carrying the plowshares and adapted to lift the frame and the plowshares suspended from it, at the end of the furrow or whenever occasion arises, above the ground.

The object of this invention is to provide improved means for lifting the frame and the plowshares in a more efficacious manner.

As usual in this type of motor plows the front end of the frame carrying the plowshares is pivoted to a crank arranged on the traction engine or motor car, said crank being adapted to be rotated either by hand or by any suitable mechanism and, on being moved from the horizontal position into an upright vertical position, lifting the front end of the frame, the back end resting on an adjustable wheel.

According to the present invention a pair of bell crank levers are arranged at the back end of the motor car. The levers are rigidly fastened to a horizontal shaft extending across the car frame, and the ends of their lower arms engage in horizontal slots near the middle part of the frame carrying the blades. Stops arranged on this frame between the slots and the ends of the upper arms of the bell crank levers serve to turn these levers and to lift the frame, whenever they are moved toward and into contact with these arms which, however, are free to follow the oscillations of the frame as long as this latter is in its working position.

The drawings annexed to this specification show the preferred form of a motor plow according to the present invention.

Figure 1 is a side elevation of the motor plow showing it in working position (in

full lines) and in the course of lifting the plowshare-frame (in dotted lines). Fig. 2 is a plan view. Figs. 3 to 5 are side elevations of the motor car and plowshares in working position (Fig. 3), in the course of lifting the plowshares (Fig. 4), and in the uppermost position of the plowshare-frame.

Referring to the drawings, A is the traction engine or motor car, B is the car frame, C is the frame carrying the plowshares or blades, E are two crank arms rigidly fixed on a cross shaft D and pivotally connected to the front ends of the frame C. The shaft D and crank arms E are adapted to be rotated in the direction of the arrow.

At the rear end of the motor car frame the cross shaft F is located, said shaft carrying a pair of bell crank levers G M. The lower arms M of the bell crank levers engage in slots H arranged in vertical shoulders P on the side bars of the frame C and serve to keep it in its horizontal working position, while the cranks E are in their lowermost position (Fig. 4), without however interfering with the vertical movements of the frame in the course of working. The upper arms G of the bell crank levers are provided with side-rollers J lying in front of the slotted shoulders P.

When the shaft D is rotated in the direction of the arrow (Fig. 4), the crank arms E fixed to it will lift the front end of the plowshare-frame C (Fig. 4), the adjustable wheel L carrying the tail end of said frame still resting on the ground. As soon, however, as the front edges K of the shoulders P have come in contact with the rollers J of the upper arms G of the bell crank levers, the crank arms drawing the frame C and shoulders P forward, the bell crank levers G M will be turned in the same direction and their arms M will lift the rear end of the frame C from the ground and the plowshares out of the furrow, the frame C finally assuming the position shown in Fig. 5. On further rotating in the direction of the arrow beyond the horizontal position shown in Fig. 5 the crank arms E will allow the bell crank levers G M to return to their initial position and the frame C to be lowered again into working position.

We claim:—

1. In a motor plow, in combination, a motor car, a plowshare-frame attached to said car, and having horizontal guides, means for pulling said frame toward the car, and a pair of levers rigidly connected with each other and pivoted to the rear end of said car, the free ends of said levers engaging in the horizontal guides on the plowshare frame. 45
2. In a motor plow, in combination, a motor car, a plowshare-frame attached to said car, and having horizontal guides, means for pulling said frame toward the car, a pair of rigidly connected bell crank levers pivoted to the rear end of said car, the lower arms of said levers engaging in the horizontal guides on the plowshare-frame, and stops on said frame between the lower and the upper arms of said bell crank levers. 50
3. In a motor plow, in combination, a motor car, a crank-shaft extending across said car, means for rotating said shaft, a plowshare-frame attached to said car and having horizontal guides, the front end of said frame being pivoted to the cranks of said crank shaft, and a pair of levers rigidly connected with each other and pivoted to the rear end of said car, the free ends of said levers engaging in the horizontal guides on the plowshare frame. 55
4. In a motor plow, in combination, a motor car, a crank shaft extending across said car, means for rotating said shaft, a plowshare-frame attached to said car, and having horizontal guides, the front end of said frame being pivoted to the cranks of said crank shaft, a pair of rigidly connected bell crank levers pivoted to the rear end of said car, the lower arms of said levers engaging in the horizontal guides on the plowshare- 60

frame, and stops on said frame between the lower and the upper arms of said bell crank levers.

5. In a motor plow, in combination, a motor car, a crank shaft extending across said car, means for rotating said shaft, a plowshare-frame attached to said car, and having horizontal guides, the front end of said frame being pivoted to the cranks of said crank shaft, a shaft extending across the rear end of said car, a pair of bell crank levers fixed to said shaft, the lower arms of said levers engaging in the horizontal guides on the plowshare-frame, and stops on said frame in front of said guides, said stops being adapted to come in contact with the upper arms of said bell crank levers. 65

6. In a motor plow, in combination, a motor car, a crank shaft extending across said car, means for rotating said shaft, a plowshare-frame attached to said car, the front end of said frame being pivoted to the cranks of said crank shaft, a shaft extending across the rear end of said car, a pair of bell crank levers fixed to said shaft, and vertical shoulders on the plowshare-frame, having horizontal slots formed therein, the lower arms of the bell crank levers engaging in said slots and the front edges of said shoulders being adapted to come in contact with the upper arms of said bell crank levers. 70

In witness whereof we have hereunto set our hands in the presence of witnesses. 75

GEORG OSCAR WIHS.
OTTO PETRI.
